(57) CLAIM

The ornamental design for a syringe device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top perspective view of a syringe device; FIG. 2 is a right side elevation view of the syringe device of FIG. 1; FIG. 3 is a left side elevation view of the syringe device of FIG. 1; FIG. 4 is a top plan view of the syringe device of FIG. 1;

FIG. 5 is a bottom plan view of the syringe device of FIG. 1;
FIG. 6 is a rear elevation view of the syringe device of FIG. 1;
FIG. 7 is a front elevation view of the syringe device of FIG. 1;
FIG. 8 is a front, top perspective view of a second embodiment of the syringe device;
FIG. 9 is a right side elevation view of the syringe device of FIG. 8;
FIG. 10 is a left side elevation view of the syringe device of FIG. 8;
FIG. 11 is a top plan view of the syringe device of FIG. 8;
FIG. 12 is a bottom plan view of the syringe device of FIG. 8;
FIG. 13 is a rear elevation view of the syringe device of FIG. 8;
FIG. 14 is a front elevation view of the syringe device of FIG. 8;
FIG. 15 is a front, top perspective view of a third embodiment of the syringe device;
FIG. 16 is a right side elevation view of the syringe device of FIG. 15;
FIG. 17 is a left side elevation view of the syringe device of FIG. 15;
FIG. 18 is a top plan view of the syringe device of FIG. 15;
FIG. 19 is a bottom plan view of the syringe device of FIG. 15;
FIG. 20 is a rear elevation view of the syringe device of FIG. 15;
FIG. 21 is a front elevation view of the syringe device of FIG. 15;
FIG. 22 is a front, top perspective view of a fourth embodiment of the syringe device;
FIG. 23 is a right side elevation view of the syringe device of FIG. 22;
FIG. 24 is a left side elevation view of the syringe device of FIG. 22;

FIG. 25 is a top plan view of the syringe device of FIG. 22;
FIG. 26 is a bottom plan view of the syringe device of FIG. 22;
FIG. 27 is a rear elevation view of the syringe device of FIG. 22;
FIG. 28 is a front elevation view of the syringe device of FIG. 22;
FIG. 29 is a front, top perspective view of a fifth embodiment of the syringe device;
FIG. 30 is a right side elevation view of the syringe device of FIG. 29;
FIG. 31 is a left side elevation view of the syringe device of FIG. 29;
FIG. 32 is a top plan view of the syringe device of FIG. 29;
FIG. 33 is a bottom plan view of the syringe device of FIG. 29;
FIG. 34 is a rear elevation view of the syringe device of FIG. 29;
FIG. 35 is a front elevation view of the syringe device of FIG. 29;
FIG. 36 is a front, top perspective view of a sixth embodiment of the syringe device;
FIG. 37 is a right side elevation view of the syringe device of FIG. 36;
FIG. 38 is a left side elevation view of the syringe device of FIG. 36;
FIG. 39 is a top plan view of the syringe device of FIG. 36;
FIG. 40 is a bottom plan view of the syringe device of FIG. 36;
FIG. 41 is a rear elevation view of the syringe device of FIG. 36; and,
FIG. 42 is a front elevation view of the syringe device of FIG. 36.
The broken lines shown in the figures are included for the purpose of illustration and form no part of the claimed design.
